UNITED STATES PATENT OFFICE.

CLAYTON J. HOWEL, OF CHICAGO, ILLINOIS, ASSIGNOR TO ORANGE CRUSH COMPANY,
OF CHICAGO, ILLINOIS.

DESIGN FOR A BOTTLE.

Application filed November 17, 1926. Serial No. 19,752. Term of patent 14 years.

To all whom it may concern:

Be it known that I, CLAYTON J. HOWEL, a citizen of the United States, residing at Chicago, Illinois, have invented a new, original, and ornamental Design for Bottles, of which the following is a specification, reference being had to the accompanying drawing, forming a part thereof.

The figure shown in the drawing is an elevation of a bottle embodying the invention.

I claim:

The ornamental design for a bottle as shown.

CLAYTON J. HOWEL.
